necessary that a super-audible frequency be supplied to the crystal from the source 12 so this energizing frequency will not interfere with the transmission of the desired signals.

5. Fig. 4, shows rectifying tube 35 in which a crystal element 36 is mounted upon a press 37 in any suitable manner and energized through electrodes 38 and 39. Positioned around the crystal structure is an anode electrode 42 which 10 is connected in a circuit through a load 43 and the secondary of transformer 44. The tube, in this instance, acts solely as a rectifier of alternating energy from a source 45 which is to be utilized by the load 43, the source 45 also serving 15 as an energy source for the crystal 36.

Now referring to Fig. 5 in which a complete radio receiving circuit is shown, an antenna 50 may be tuned by a variable condenser 51 shunting the primary of input transformer 52, which is 20 connected to the input of a radio frequency amplifying tube 54. The input circuit of this tube may be tuned by a variable condenser 55. The tube 54 is identical with that shown in Fig. 1 and will 25 thus not be further described.

25. The output of tube 54 is coupled to rectifying detector 55 through an interstage transformer 56. The tube 55 is similar to the tube shown in Fig. 3 except that a condenser-resistance combination 57 is employed for detection. The output of tube 30 55 is coupled through a transformer 58 to an audio amplifying tube 59, this tube being similar to the tube in Fig. 1 except that it employs a cylindrical crystal element 65 having a band electrode 60 encircling its mid-section and an end electrode 61. The output of the amplifier 59 is 35 connected to a loud speaking device 67 and a source of potential 62. This source 62 not only supplies tube 59, but also tubes 54 and 55 over conductors terminating in variable taps 63 and 40 64. A source of potential 66 supplies alternating voltage for producing ionization for all the tubes over an obvious circuit. Bypass condensers 68, 69 and 70 function to eliminate alternating currents from the high potential sources, that is, 45 these condensers shunting the source 62, by-pass the alternating components in the output circuits of tubes 54, 55 and 59, respectively. The grids of the respective tubes are connected to potentiometer resistances 73, 74 and 75 for the 50 purpose of eliminating any hum effect from the source 66, it being understood that one potentiometer may also serve for this purpose, the control electrodes being connected thereto. A source of direct potential 77 provides the proper 55 bias for the tube 59.

Although only a few types of amplifying and rectifying circuits have been illustrated and described for purposes of explanation, it is to be understood that other equivalent circuits will 60 occur to those skilled in the art and these are deemed to be within the scope of the appended claims.

What is claimed is:

1. In an electrical transmission system, an input circuit, an output circuit, a piezoelectric ionization element, a control electrode connected to said input circuit, an anode connected to said output circuit, a plurality of electrodes for said element connected to an alternating current source, and means for connecting said plurality of electrodes to a common point on said input and output circuits.
2. In an electrical transmission system, a repeating device comprising a partially evacuated envelope having an anode, a control electrode

and a piezoelectric crystal element for ionizing gas in said envelope, a plurality of electrodes for said crystal for connecting said crystal to an alternating current source, an input circuit connected between said control electrode and a mid-point between said plurality of electrodes, an output circuit connected between said anode and said mid-point, and means for impressing signaling energy on said input circuit.

5. 3. In an amplifying system, an input circuit, an output circuit, a vacuum discharge device comprising a partially evacuated envelope having a plurality of electrodes and a piezoelectric crystal element positioned between two of said electrodes, one of the other of said electrodes being connected 10 to said input circuit and another of said electrodes being connected to said output circuit, means connected to said crystal electrodes for energizing said crystal element with alternating current, and means for connecting said input and 15 output circuits to said energizing means for neutralizing alternating components in said energizing means.

4. In an amplifying system, an electrical discharge tube comprising a partially evacuated envelope having an anode and control electrode therein, said device also including a piezoelectric crystal element having a pair of supply electrodes directly connected to an alternating current energy source, means for connecting said control electrode to one of said supply electrodes, an input circuit connected between said control electrode and said one supply electrode and said other supply electrode, and an output circuit connected between said anode and said second mentioned 35 supply electrode.

5. In an electrical translation system, an antenna circuit, means for tuning said circuit, a vacuum discharge device connected to said tuned circuit, having a crystal ionization element therein, 40 means for connecting said device to a second crystal ionization device for demodulating signals received over said antenna circuit, an audio frequency amplifying tube having a crystal ionization element therein, means for coupling said demodulating device to said audio frequency amplifying tube, a second reproducing device connected to the output of said audio frequency amplifying tube, means for energizing said crystal ionization element in parallel from a common alternating current source, means for polarizing the control electrodes of said amplifiers, and means for neutralizing the alternating components of said energizing currents, said means including a connection 50 from the electrodes of said device to points having the same potential in said energizing means.

6. In a plural stage electrical translation system, a plurality of glow discharge tubes having a plurality of cold electrodes in each of said tubes, a crystal ionization element positioned in each of said tubes between two of said cold electrodes in each tube, means connected to said two electrodes in each tube for energizing said crystals, an input circuit for one of said tubes connected from a point between said crystal electrodes and to another of the electrodes thereof, an output circuit for said tube connected between said crystal electrodes and a second of the electrodes thereof, an input circuit for another of said tubes connected to the crystal electrodes thereof said circuit including an impedance, and means including said impedance for coupling the output circuit of said first tube with the input circuit of said second tube.

7. In a plural stage electrical translation system, a plurality of glow discharge tubes having a plurality of cold electrodes in each of said tubes, piezoelectric crystals in said tubes, said crystals being positioned between two of said electrodes in each tube, an input circuit for a radio frequency tube connected from a point between the crystal electrodes of said tube to another electrode thereof, an output circuit for said tube connected from a point between said crystal electrodes and a second electrode thereof, an input circuit for a detector tube coupled to said output circuit, said input circuit being connected between the crystal electrodes of said detector tube, means connected to said crystal electrodes for supplying said crys-

5 tals with alternating current, and means connected across said supply means for neutralizing said alternating current during transmission of signals through said tubes.

8. In an electrical transmission system, a partially evacuated envelope an input circuit, an output circuit, a crystal ionization element within said envelope, a control electrode within said envelope connected to said input circuit, an anode within said envelope connected to said output circuit, a plurality of electrodes adjacent said ionization element connected to an alternating current source, and means for connecting said plurality of electrodes to said input and output circuits.
